(57) **CLAIM**

I claim the ornamental design for a material level indicator actuator, as shown and described.

DESCRIPTION

FIG. 1 is a front elevational view of a material level indicator actuator showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a sectional view taken along line 6-6 of FIG. 2; and,

FIG. 7 is a rear elevational view thereof.
